UNITED STATES PATENT OFFICE

LOUIS H. MORIN, OF NEW YORK, N. Y., ASSIGNOR, BY MESNE ASSIGNMENTS, TO
DOEHLER VENDING MACHINES, INC., OF NEW YORK, N. Y., A CORPORATION OF
NEW YORK

COIN-CONTROLLED MECHANISM

Application filed December 7, 1927. Serial No. 238,238.

While the coin controlled mechanism of the present invention is shown in the accompanying drawings as embodied in a machine for vending paper towels it is to be understood as obvious that this invention substantially as disclosed or with suitable modification therein may be employed for other purposes and may be embodied in vending machines of various types and kinds or in other forms of dispensing or service-supplying devices. While the present invention is substantially differentiated from that disclosed and claimed in my prior copending application Serial No. 39,442, filed June 25, 1925, which became Patent No. 1,723,948, August 6, 1929, some of the features of that invention are retained in substantially similar form in the disclosed embodiment of the present invention, of which the magnet feature is claimed in my copending divisional application Serial No. 133,615, filed September 4, 1926, which became Patent No. 1,657,836, January 31, 1928, while the feature by which the coin carrier is locked in a position to close the coin slot against the insertion of a coin when the magazine of the delivery mechanism requires replenishing is substantially similar to that claimed in my copending application Serial No. 205,285, filed July 13, 1927, which became Patent No. 1,728,901, September 17, 1929. The dispensing features disclosed herein, as distinguished from and to the exclusion of the coin controlled features claimed herein, are claimed as a divisional part hereof in my copending application Serial No. 273,169, filed April 27, 1928, for Web dispensing device, which became Patent No. 1,738,721, December 10, 1929. An object of the present invention is to effect the extensive unidirectional rotation to a predetermined extent of a rotatable operating member the unidirectional rotation of which is to be utilized for supplying the desired service. Another object of the invention is to provide for the continued unobstructed or uninterrupted service-supplying rotation of this operating member by the successive feeding of coins to the coin controlled mechanism prior to the completion of the predetermined extent of rotation of this mem-

ber which is determined by the insertion of each separate coin. Other objects of the invention are to provide a coin controlled mechanism of this kind which is simple, strong, durable, effective, compact, easy to manufacture, and which is particularly adapted for heavy duty work. Other objects and advantages of the invention will hereinafter appear.

In accordance with the invention a pair of continuously manually rotatable driving members are positively connected or coupled together at all times for the unlimited concurrent rotation of these connected driving members. One of these driving members during its continued rotation causes to and fro movement of a coin carrier while the driving member continues its rotation. When the coin carrier carries no coin it may be thus repeatedly operated idly while the other or second driving member rotates idly with the first driving member which operates the coin carrier. A continuously unidirectionally rotatable operating member the rotation of which is to be utilized is normally idle and disconnected from the rotatable driving members but may be positively connected or clutched to the second driving member to be rotated thereby. A coin moved by the coin carrier operates a coupling device by which the rotatable operating member is coupled or clutched to the second driving member and which automatically disconnects the operating member from the driving member when the operating member has been rotated to the desired predetermined extent for rendering service which is the equivalent of the coin. This coupling device operates on the principle of a one-revolution clutch. However, the construction is such that by supplying the returned coin carrier with another coin before the operating member has completed a predetermined extent of rotation the operating member will remain clutched to the driving member and may continue its service-supplying or dispensing rotation indefinitely by thus feeding successive coins to the coin carrier.

More particularly, in carrying out the invention, the coin carrier is rocked on a pivot

while the two driving members and the operating member are coaxial and have unitary rotation. The first driving member, which may be a cam or the like, rocks the coin carrier and releases it to be returned by a spring, during a part of one rotation of this driving member, while both driving members continue their rotation, and the operating member being limited to one complete rotation resulting from the insertion of a single coin. The rotatable operating member forms the initial driving or operating member for the dispensing or service-supplying device, which in the present instance and as above noted vends paper towels, these towels being contained in the machine in the form of a continuous web, any desired uninterrupted length of which may be obtained by successively inserting a corresponding plurality of coins one after the other thereby to render the delivery operation of the machine continuous, as above noted. The invention further includes various features of construction and combinations of parts as will appear from the following description.

One embodiment of the invention which is illustrated in the accompanying drawings will now be described and thereafter the invention will be pointed out in claims, reference now being had to the drawings, in which:

Fig. 1 is a front elevation of a vending machine embodying the invention;

Fig. 2 is a horizontal section substantially on the zig-zag line 2—2 of Fig. 1;

Fig. 3 is a vertical section substantially on the line 3—3 of Fig. 4, taken for the most part just back of the front plates and front door, showing parts of the coin controlled mechanism and of the delivery mechanism in front elevation;

Fig. 4 is a vertical section substantially on the zig-zag line 4—4 of Fig. 3;

Fig. 5 is for the most part a vertical section taken on the zig-zag line 5—5 of Fig. 6;

Fig. 6 is a somewhat irregular vertical section substantially similar to Fig. 4 but showing the coin controlled mechanism and some other parts in side elevation and also showing the magazine of the machine as empty;

Figs. 7, 8, 9 and 10 are enlarged partial front views similar to Fig. 3 and show successive phases of operation of the coin controlled mechanism;

Fig. 11 (Sheet 1) is an individual rear elevation of the rotatable operating member and some of its immediately associated parts substantially as viewed from the vertical line 11—11 in Fig. 6 or as similarly viewed in Fig. 4, and

Fig. 12, is a similar enlarged view with the peripheral parts broken away to save space.

In the embodiment of the invention illustrated in the accompanying drawings and now to be particularly described, the oper-

ating mechanism of the machine is contained within a rectangular casing box which may be formed of suitable sheet metal such as steel by means of ordinary stamping and welding operations. This casing box has a bottom 1, back 2 from which the machine may be conveniently supported so as to leave its bottom clear, right and left side walls 3 and 4, a front door 5 and a cover or top door 6. The front door 5 is hinged along its right edge at 7 and the top door 6 is hinged along its rear edge at 8.

The front door 5 is cut out adjacent its left edge to expose upper and lower front plates 9 and 10 of the framework of the coin controlled mechanism. The lower front plate 10 is secured by means of screws 11 from the inside to a main frame plate 12 in parallel spaced relation therewith. This main frame plate is provided with a plurality of flanges, projections and bosses for various purposes including its rearward spacing from the front plates 9 and 10. This main frame plate 12 is shown as firmly secured to the front door 5 by means of rivets 13. The upper front plate 9 at its lower edge engages behind the upper edge of the lower front plate 10 and is firmly but removably secured in place adjacent its upper end and to the main frame plate 12 by means of an inside thumb screw 14. Thus in the construction shown the coin controlled mechanism is carried by the swinging front door 5.

The front door 5 also carries at the inside thereof a removable coin box shown as comprising a rectangular body portion 15 which is permanently closed at its front by a plate 16 secured thereto and which is provided at its left side adjacent its top and front with an opening 17 for the entrance of the coins and through which they may be emptied out when the coin box is removed. The front plate 16 projects beyond the box body 15 to form a flange which is slidably received at the front of gibs providing guideways on the door 5 so that the coin box may be removed by upward sliding movement. This coin box may be locked in place on the front door 5 by means of a key-operated lock 18 riveted to the inside of the door at the right side of the coin box and having a partially rotatable bolt or catch 19 to engage in a notch cut in the right side of the coin box, as shown in Figs. 1 and 2. This coin box lock 18 is accessible for operation only from the inner side of the opened front door 5.

The casing structure further includes a container or magazine box in the rear thereof, the rear wall of which is formed by the back wall 2 of the outer casing. This magazine box is of rectangular shape and has a bottom wall or floor 20 spaced above the outer casing bottom 1, a front wall 21 spaced rearwardly from the front door 5 and shown as provided with a large central opening, a right side wall 22

22 spaced inward from the right casing wall 3 and a left side wall 23 spaced inward to a somewhat greater extent from the left casing wall 4. The right and left side walls 22 and 23 have at their upper ends inturned wings 24 and 25 which form paper guides at the front of and slightly spaced from the front wall 21. Transverse bracing rods 26 and 27 are provided over which respectively the upper edge of the front wall 21 and the upper ends 10 of the guide wings 24 and 25 are turned away from each other to form rounded edges or beads.

A paper towel web 28 is contained in the magazine in the form of a fan-fold pack from the top of which this web extends over the top of the front wall 21 behind the guide wings 24 and 25 and continues downward and out through a slot in the casing bottom where it is 15 guided at its back by a rear guide strip 29 which forms a rounded shoulder and is guided at the front by a bent guide strip 30 which projects downwardly and rearwardly at an inclination below the casing bottom 1 where 20 it is provided with a sharp cutting edge over which a strip of the towel web 28 of the desired length may be torn off. Instead of the paper towel web 28 being in the form of a fan-fold pack, as shown, this web might be 25 contained in the magazine in the form of a roll carried by a suitable spindle or the like. Also, it is obvious that this web need not necessarily be paper toweling, but might be a paper or other suitable web to be used for any 30 purpose desired.

A visual indicator is provided for showing at any time upon inspection the size of the pack of towel web 28 contained in the magazine. This indicator comprises a roller 31 to rest upon the top of the pack, journaled in a bracket 32 which is pivoted on the horizontally turned end of a rod forming an indicator lever 33 which extends through a slot in the top of the left magazine wall 23 and 40 has a forwardly extending shaft portion journaled in rear and front supports 34 and 35 which are secured to the left casing wall 4. The forward end of this shaft portion is turned inward to form a pointer 36 which 45 may move at the front of an indicating plate 37 which extends from the front support 35. This indicator plate 37 is shown as graduated and as provided with the upper end and lower legends "Full" and "Empty". The indication 50 is visible through a window in the front door 5 which is closed by a glass plate 38 supported by a holder 39 secured to this door. The magazine bottom 20 is shown (Fig. 2) as provided with a slotted opening into which 55 the indicator roller 31 may drop (Fig. 6) when the supply of towel web 28 is exhausted, thereby to give a more positive indication of the pointer 36 that the magazine requires replenishing.

60 Near the lower left hand corner of the

front door 5 the main frame plate 12 carried thereby is provided with a keeper 40 to receive the lower end of a vertically slidable latch rod 41 which is guided through lower and upper ears 42 and 43 formed on an extended portion of the front magazine wall 21, and is urged upwardly to disengage the keeper 40 by a coiled thrust spring 44 interposed between the lower ear 42 and a collar on the latch rod. The upper end of this latch rod is turned over horizontally to engage beneath the brace rods 26 and 27 for holding the latch rod down and may be disengaged therefrom by rotating the latch rod, whereupon its spring 44 will disengage it 70 from the keeper 40. The front door 5 is further secured in closed condition by means of a flange along the forward edge of the top door 6 which fits down over the upper edge 75 of this front door. The top door 6 is secured in closed condition by means of a key-operated lock 45 carried thereby to be operated from the outside of the casing and having a catch or lock bolt 46 to engage beneath a keeper lug 47 riveted to the inner side of the front door 5. Thus by unlocking the lock 45 both of the doors 5 and 6 may be opened or the top door 6 alone may be opened for replenishing the magazine through its open 80 top.

Close above the guide strips 29 and 30 and immediately below the lower edge of the front magazine wall 21, which is shown as projecting downward below the bottom wall 20, the paper towel web 28 is firmly gripped and securely held between a pair of substantially similar front and rear soft rubber feed rollers 48 and 49 by which, under coin control, it is normally restrained against being pulled out. These rollers are respectively molded upon metal, such as brass, core tubes 50 and 51 so as to be firmly secured thereto. Substantially similar bearing ends or plugs 52 and 53, which may be formed from the same die-casting, are respectively fixed in the front and rear roller core tubes 50 and 51 at their right hand ends. Also bearing ends or plugs 54 and 55 substantially similar to each other are fixed in the left hand ends of the respective front and rear roller core tubes 50 and 51. The rear roller 49 is mounted within the machine casing body while the front roller 48 is carried by the front door 5 to swing outward therewith, thereby providing for the easy insertion of the paper towel web 28 between these rollers.

The outer ends of the left hand end bearings 54 and 55 are provided respectively with similar intermeshing spur gears 56 and 57 by which the two feed rollers 48 and 49 are positively connected together for cooperating rotation. Also, somewhat smaller spur gears 58 and 59 are formed on the respective end bearings 54 and 55 adjacent the ends of the respective rollers 48 and 49. Each of the

end bearings 54 and 55 together with its two gears may be die-cast in one piece. The forward smaller spur gear 58 on the bearing end 54 is utilized for driving the two feed rollers but the corresponding smaller gear 59 on the end bearing 55 for the rear roller 49 is not used and is present only because, for convenience of manufacturing, the same die-casting is used for forming the two end bearings 54 and 55, each together with its gears cast thereon.

A shaft 60 for the rear feed roller 49 is fixed in its end parts 53 and 55 beyond which it projects and at its reduced outer ends is journaled in bearing blocks 61 which are slideable horizontally in guideways 62 secured to the respective side walls 3 and 4 of the casing. Each of these guide brackets 62 is provided with a coiled thrust spring 63 urging the bearing block 61 forwardly to press the rear feed roller 49 against the front feed roller 48, cotter pins 64 being provided through the front ends of the guide brackets 62 to prevent the escape of the rear feed roller 49 when the front feed roller 48 is swung away from it.

The front feed roller 48 is journaled on the inturned ends of a bracket bar 65 which is secured by rivets as shown to the front door 5. The right end of this bracket bar carries a cone-shaped pivot pin 66 which forms a bearing for the right hand bearing end 52 of this front roller. The left hand end of this bracket bar 65 has threaded through it an adjustable bearing screw 67 which forms a cone-bearing for the left hand gear-carrying bearing end 54 of this front feed roller and which is provided with a lock nut 68.

40 The feed rollers 48 and 49 are normally locked and in operation are positively driven by the coin controlled mechanism through the intermediary of a train of toothed gears. These intermediary or connecting gears, 45 which are shown as five in number, are journaled on and carried by a downward extension of the main frame plate 12. The smaller spur gear 58 of the front roller 48 is engaged by an idler gear 69 which in turn is engaged by a spur gear 70 which at the left side thereof has a miter gear 71 formed thereon. A spur gear 72 similar to the spur gear 70 and having its axis at right angles thereto has similarly formed thereon a miter gear 73 55 which engages with the miter gear 71 at the rear side thereof. These two spur gears 70 and 72 together with their respective miter gears 71 and 73, which may be formed respectively in one piece therewith, may be substantial duplicates. The latter spur gear 72 is engaged by an intermediary or idler gear 74 located at the right thereof as viewed from the front in Figs. 3 and 5; this spur gear 72 being behind or at the back of the intermediate gear 74 as viewed from the right side of

the machine in Figs. 4 and 6 and being thus indicated by dotted lines in Fig. 4.

This entire train of gearing for rotating the feed rollers 48 and 49 is driven by power applied through the coin controlled mechanism to the intermediate gear 74 to rotate the latter. In the embodiment of the invention shown a normally idle and locked rotatable operating member 75 of the coin controlled mechanism takes the form of a large spur gear 75 located above the intermediary gear 74 and having intermeshing driving connection therewith. It should be noted as merely incidental to the disclosed construction of the above described dispensing or delivery mechanism that the rotatable operating member 75 of the coin controlled mechanism takes the form of a gear. In a coin controlled machine of a different type this rotatable operating member 75 could as well take a different form in which it would not be a gear. For example, it might be a rotatable cam and, in fact, a coin controlled machine has been constructed in which a similar rotatable operating member is a cam. In the construction shown, this rotatable operating member or gear 75 may be properly said to form an initial drive member for the feed rollers 48 and 49, in that this operating member or drive gear 75 is the first part or first gear in the series of driving connections which at all times has a positive connection with these rollers, as above noted.

The rotatable operating member or initial drive gear 75 constitutes a part of the coin controlled mechanism, as above noted, and the remaining parts of the coin controlled mechanism for rotating this operating member and for positively determining the extent of its rotation will now be described.

A rocking coin carrier 76 of generally segmental or arcuate shape, to extend above, below and to the left of its axis, is located in and substantially fills the space between the front frame plates 9 and 10 and the main frame plate 12. At its front the coin carrier 76 is provided with a pivot stud 77 which is journaled in the lower front plate 10, and at its rear the coin carrier is similarly pivoted on the main frame wall 12 in axial alignment with the front pivot stud 77 by means of a similar pivot stud (not shown) which projects from this frame wall 12 into the coin carrier. The backward or return movement of the coin carrier is limited by a stop lug or shoulder 78 on the frame plate 12 to be engaged by the coin carrier at the right thereof and below its axis. Any possibility of overthrow of the coin carrier taking place in its forward rocking movement is prevented by an upper stop lug 79 to be engaged by a shoulder 80 on the coin carrier at the left thereof, this upper lug 79 also having other functions, as will presently appear.

At its top or upper end the coin carrier is provided with a transverse coin holding slot 130

81 to receive the lower edge of a coin 82 inserted through a coin slot 83 in the upper front plate 9 and with which the coin carrier slot 82 is normally in alignment, as indicated in dotted lines in Fig. 1. The upper portion of the coin is guided by the right side of the frame lug 79 against which it may rest. The upper edge of the coin is received between and the coin is positioned by the spaced poles 10 of the arms of a curved horseshoe magnet 84 which is normally pressed against the stop lug 79 by a spring 85, this magnet being pivoted in a notched lug 86 on the frame plate 12 and loosely held in place by a screw 87. 15 For discarding paramagnetic slugs the magnet is rocked by a cam lug 88 on the coin carrier which successively engages a pair of small rollers 89 on the magnet.

The coin is moved by a finger 90 which 20 engages substantially the center of the coin and which projects from an inclined shoulder on the coin carrier, as shown, so that this finger is also effective to discard washers. As the coin is moved by the coin carrier its 25 upper edge engages an adjacent lower tooth of a star wheel 91 and imparts one step of rotative movement thereto. In carrying out the invention, this star wheel forms the primary operating element of a coupling device, as will hereinafter appear. The star wheel 91 is fixed upon the forward end of a star wheel shaft 92 which is journaled in a bearing on the upper part of the main frame plate 12.

30 As soon as the coin carrier starts its return movement the coin carried thereby will drop upon the inclined floor 93 of a coin chute and slide into the coin box 15 through its opening 17. This coin chute, which is formed on the main frame plate 12, also has an upper or top wall 94 to assist in guiding the coins through the opening 17 into the coin box. Disengagement of the coin from the returning coin carrier is assured and the 35 jamming of the coin against a tooth of the star wheel 91 prevented by a kick-off pawl 95 pivoted on the frame 12 at 96 and having a spring 97 which normally urges it against a stop 98 with its free end in the path of the 40 upper edge portion of the coin.

The coin carrier is returned to and normally maintained at its normal retracted position by a retractile coiled spring 99 anchored at one end to a lug on the frame 45 plate 12 and at its other end connected to the lower part of the coin carrier through the intermediary of a flat bent lever 100 pivoted to the lower end of the coin carrier on a pivot pin 101 and located in a deep slot 50 in the coin carrier at the right. The upper end of this lever normally abuts against the bottom of this slot and forms a feeler for a coin in the coin holding slot 81, across which it may pass when this slot is empty 55 but will be stopped by a coin therein. This

result is brought about by a pair of reversible pawls 102 pivoted on the lower end of the lever 100 which extends towards the left, and urged by springs 103 to a middle position to wipe over and escape from the opposite ends of a saw-tooth ratchet 104 fixed on the main frame plate 12. A coin in the coin carrier slot 81 prevents the reversal of these pawls on the ratchet 104 and thereby prevents the return of the coin carrier 76 from an intermediate position with the probable consequent loss of the coins in the machine. The construction of the coin carrier and the parts related thereto as so far described are substantially similar to the disclosure in my above noted Patent No. 1,723,948, with the exception that in carrying out the present invention the star wheel 91 has a different specific function.

Some lost motion is provided between the upper edge of the coin 82 and the adjacent tooth of the star wheel 91 so that the coin will be moved out of alignment with the coin slot 83 in the upper front plate 9 before the coin begins to rotate the star wheel. As soon as the coin is moved out of alignment with this coin slot the coin carrier 76 will then obstruct this slot against the insertion of another coin until the coin carrier has been returned to its normal position. Means are provided to maintain the coin carrier 76 in a position to close the coin slot 83 when the magazine becomes empty, thereby to prevent the loss of coins in the machine. For this purpose a locking lever is provided, shown as formed of a single bent rod having a horizontal shaft portion 105 pivoted in a bearing 106 on the main frame plate 12 adjacent its lower right hand corner at the back thereof.

This shaft 105 at the left of its bearing 106 has an upstanding locking arm 107 provided with a forwardly projecting locking end 108 to be projected through a hole 109 (Fig. 3) in the frame plate 12 beyond the forward face thereof and into the path of the lower right hand portion of the returning coin carrier 76, thereby to stop the return movement of the coin carrier before it has uncovered the coin slot 83. A spring 110, engaging with the arm 107, urges the locking end 108 towards its projected position in the return path of the coin carrier. At the other or right end of the bearing 106 the shaft 105 is provided with a downwardly and rearwardly extending lever arm 111 which terminates in a horizontal end portion 112 extending towards the left in parallel relation with the shaft 105. This end portion 112 carries a roller 113. Just above the magazine bottom 20 the front wall 21 of the magazine has a tongue 114 struck back therefrom which forms a recess at the front thereof at the rear of the roller 113, which forms a feeler for the paper towel web 28.

The towel web 28, just at the front of the front wall 21, holds the roller 113 out of the recess formed by the tongue 114 and accordingly holds the locking end 108 out of the return path of the coin carrier 76, as shown in Fig. 2 and as indicated for the roller by broken lines in Fig. 6. When the towel web 28 is exhausted, as shown in Fig. 6, the spring 110 will swing the roller 113 into the recess formed by the tongue 114 and will project the locking end 108 into the return path of the coin carrier 76. The upstanding arm 107 which carries the locking end 108 is guided adjacent the latter by a pair of lugs 115 on the back of the frame plate 12. The above described slot closing device is substantially the same as that disclosed and claimed in my above noted Patent No. 1,728,901.

Manually operable means now to be described are provided in accordance with the invention for rocking the coin carrier 76 to and fro regardless of whether or not it carries a coin, and when it carries a coin for then rotating the rotatable operating member or 25 drive gear 75 and for continuing its unidirectional operating rotation after the coin carrier has been returned by its spring 99 to its normal retracted position.

According to the invention, a pair of continuously rotatable driving members are provided which are positively connected or coupled together for normal unlimited concurrent unidirectional rotation. One of these driving members is at all times normally effective to rock the coin carrier 76 successively as this driving member continues its rotation, while the other or second driving member, which is for rotating the operating member or drive gear 75, is normally ineffective and may rotate idly and to which the rotatable operating member 75 may be positively connected or coupled to be rotated thereby by means of a clutching or coupling device operated by a coin moved by the coin carrier 76. This coupling device is so constructed that after a predetermined extent of rotation of the operating member 75 the latter will be automatically disconnected from its driving member but so that such driving connection will be maintained should another coin be supplied to the returned coin carrier 76 in the meantime, whereby a strip of the paper towel web 28 of any desired length may be thus obtained. The particular construction of the mechanism illustrated in the drawings for carrying out the invention in a practical embodiment thereof to produce the above noted results will now be described.

In the embodiment of the invention shown, the coin carrier 76 is cam-operated and accordingly is provided with a cam follower shown as a stud 116 which projects forwardly from adjacent its left margin and carries a small anti-friction roller 117. Normally the cam roller 117 lies in the path of the cam rise

of a rotatable cam the axis of which is spaced from and in parallel relation to the axis of the coin carrier 76. This cam is shown as a substantially radial rounded cam arm 118 the axis of which is between and substantially 70 in alignment with the axis of the coin carrier and the cam roller 117 in the normal position of the latter and of the coin carrier shown in Fig. 3. As the cam 118 is rotated in the forward or clockwise direction as viewed from the front it will rock the coin carrier 76 away from its normal retracted position shown in Fig. 3 successively through the positions shown in Figs. 7 to 10 inclusive. The cam arm 118 is made of a length so that it will 75 pass beyond and release the cam roller 117 when the coin carrier 76 has been rocked forwardly to the desired extent. A further very slight rotation of this cam beyond the position thereof shown in Fig. 10 will release the cam roller 117, whereupon the coin carrier 80 spring 99 will return the coin carrier to its normal position shown in Fig. 3 while the cam 118 may continue its rotation, in which after one complete rotation it will be brought 85 back again to the normal position thereof shown in Fig. 3, after which the rotation may be continued for again rocking the coin carrier as before and so on.

The cam 118 is provided with a sleeve 119 which extends inwardly through a large slotted arcuate opening through the coin carrier 76, and this cam also is provided with a head 120 journaled in a tubular boss 121 formed on the front of the lower front frame plate 10. The cam 118 is shown as formed in one piece with its sleeve 119 and its head 120, immediately adjacent the rear face of the latter. Between the coin carrier 76 and the cam head 120 the front wall 10 is recessed around and outwardly beyond the head 120 to provide a space for the rotation of the cam arm 118 and for the arcuate movement of the follower stud 116 and its roller 117, as shown in Fig. 4.

Instead of the cam 118 and its follower 117, it should be evident that some other device having a similar manner of operation might be employed for rocking the coin carrier 76. For example, the coin carrier could have a rack thereon such as shown in my above noted Patent No. 1,723,948 and the sleeve 119 could be in the form of a mated or segmental pinion for rocking the coin carrier forward and then releasing it 105 during the continued rotation of such segment. In fact, the cam arm 118 may be considered as forming in effect a one-tooth pinion and the follower stud 116 together with its roller 117 as forming a one-tooth 110 rack, since the manner of operation is substantially the same.

In the embodiment of the invention shown, the driving member for the operating member 75 is coaxial with the driving arm 118 115

and is shown as a disc 122 spaced rearwardly somewhat beyond the back of the frame plate 12 and provided at its front with a hub sleeve 123 journaled in a bearing extending through the main frame plate 12 and at its rear this disc is provided with a hub boss 124. At its forward end the hub sleeve 123 is provided with a square-shouldered diametral rib which seats in a corresponding complementary diametral groove in the rear end of the hub sleeve 119 of the cam 118, as shown in dotted lines in Fig. 4, so that thereby the driving disc 122 is positively connected to the driving cam 118 for unitary rotation therewith.

The driving head 120 of the cam 118 is shaped to form the cup element of a friction driving clutch of the cone type and having a cooperating cone element 125. A rotatable handle knob 126 has a reduced hub portion journaled in the reduced outer end of the bore in the front boss 121 and is positively connected to the cone element 125 to rotate the latter by means of a square-faced diametral groove in the handle knob hub in which is seated a complementary square-shouldered diametral ridge on the adjacent outer face of the clutch cone 125, as is shown in dotted lines in Fig. 4. A handle shaft 127 extends inwardly through the handle knob 126, cone clutch element 125 and loosely through driving cam 118 and driving disc 122. This shaft has a head 128 fixed on its forward end and fitting loosely in a bore or recess 129 in the front of the handle knob 126. As it is desirable that the handle shaft 127 shall rotate with the handle knob 126, the head 128 is provided with small wings to engage and slide in longitudinal grooves in the handle knob 126 at the outer end of its bore 129 (Figs. 1 and 4). A coiled compression spring 130 on the handle shaft 127 is interposed between its head 128 and the bottom of the enlarged bore 129 in the handle knob. This spring is adjustably maintained under suitable tension by a nut 131 on the inner end of the handle shaft 127 engaging a washer 132 which abuts against the inner end of the hub boss 124 on the driving disc 122.

The spring 130 thus maintains the clutch elements 120 and 125 in frictional driving engagement. The cone clutch element 125 will slip on the cup clutch head 120 to prevent breaking any part of the mechanism, which otherwise might occur in an attempt to rotate the handle knob 126 backwardly, in which case the back of the cam arm 118 will strike against the cam roller 117 of the returned coin carrier 76. Also, when the coin carrier 76 is stopped and locked against full return movement by the locking end 108 of the locking arm 107 the coin carrier then also is locked against its normal free forward movement by reason of the fact that

in the particular construction shown the coin carrier pawls 102 will not reverse on the ratchet 104 to permit forward movement of the coin carrier from its partially returned position, and in this case the cam roller 117 would limit the rotating movement of the cam 118 in both directions. This friction driving clutch connection just described is substantially the same as that disclosed in my above noted Patent No. 1,723,948, but is more compact by reason of the housing of the clutch spring 130 within the handle knob 126.

In the embodiment of the invention shown, the normally idle rotatable operating member 75 is coaxial with and is directly mounted upon its driving member 122, which normally may be rotated freely to an unlimited extent independently of the rotatable operating member 75 with the latter locked against operating rotation (see more particularly Figs. 3 to 6 inclusive). The operating member or drive gear 75 is circularly recessed at the back to fit around the driving disc 122 and is apertured at the front to fit around the disc sleeve 123 in the space between this disc and the bearing for its sleeve on the frame wall 12. This operating member 75 is further supported upon the drive member 122 by means of a back plate or cover plate 133, recessed or countersunk into the back thereof and fitting around the disc hub boss 124 which extends through it. This plate 133 is firmly secured to the operating member 75, such as by means of a pair of screw pins 134 and 135.

The circular driving disc 122 is peripherally notched to provide an abrupt driving shoulder 136 which faces in a clockwise direction and is shown as radial and as located at about 90° in advance of the radial driving face of the coin carrier cam or driving member 118, as will be evident by a comparison of Figs. 3 and 5 and which also is shown in each of Figs. 7 to 10 inclusive. A normally disengaged coupling pawl 137, shown as of substantially lune shape, to have in part a cylindrical surface and in part a concave arcuate surface complementary to the circular periphery of the drive disc 122 and disposed immediately adjacent thereto, to be rocked into its peripheral notch so as to be engaged by its driving shoulder 136, passes through the operating member 75 in a rather deep arcuate notch in the wall of the circular recess therein which contains the driving member 122. In the normal or idle position of the operating member 75 the pivotal axis of this pawl 137 is above the axis of rotation of the driving disc 122 substantially in vertical alignment therewith, and the left edge or point of this pawl which is to be engaged by the driving shoulder 136 is circumferentially spaced in a clockwise direction therefrom to a considerable extent to provide lost motion, as shown in Fig. 5, but which ap-

pears as somewhat less in Fig. 7 by reason of the fact that as there shown the driving disc 122 has just begun its forward rotation.

This coupling pawl 137 is provided at the rear end thereof with an axial stem or shaft portion 138 which is pivoted in the back plate 133 of the operating member 75 and projects rearwardly beyond this plate. The projecting end portion of this stem 138 carries a coiled torsion spring 139 one end of which is seated in a diametral slot in the stem and the other end of which is extended and anchored to the operating member 75 by the plate screw 135 (Figs. 4, 6, 11 and 12). As is perhaps most clearly shown in Fig. 12, this spring constantly urges the coupling pawl 137 to rock towards its engaging position, which is clockwise as viewed from the rear in Figs. 11 and 12 and counter-clockwise as seen from the front in Figs. 5 and 7 to 10 inclusive.

At its forward end the coupling pawl 137 is provided coaxially therewith with a flat circular head 140 which is countersunk into the front face of the operating member 75 down to the forward face of the driving disc 122, a portion of the operating member 75 being cut away inwardly to the drive disc sleeve 123 to provide space for the pawl head 140, the periphery of which is immediately adjacent this sleeve 123 (Figs. 4 and 5). Near its lower edge the pawl head 140 is provided with a forwardly projecting pawl-actuating or pawl-disengaging pin or stud 141 which in the normal disengaged position of the pawl 137 is positioned in radial line with the axes of the pawl and the driving disc 122 and is directly below the pivotal axis of the pawl (Figs. 4, 5 and 7).

Because of its general shape and its manner of operation, this coupling pawl 137, considered as a whole, may be termed a drive finger. This organization of the gear-forming operating member 75, with its driving member 122 and its clutch pawl 137 both substantially housed therein, provides a very compact construction. At its rear this operating member or drive gear 75 may be provided with a wide projecting flange (not shown) which forms a guide for the towel web 28 to prevent the possibility of this web catching upon or being torn by the adjacent end of the handle shaft 127 or that of the pawl stem 138.

The coupling pawl or clutch pawl 137 is normally held at its disengaged position against the tension of its engaging spring 139 by means of a movable abutment, forming a trip latch for the pawl, which is shown as a flat lever arm 142 extending at a downward inclination towards the left and the free end of which forms an abutment for the pawl stud 141. This lever arm 142 forms one of the arms of a three-armed latch lever which is fixed upon the rear end of a pivot

shaft 143 which is journaled, as shown, in a bearing on the main frame plate 12 towards the right and upper part thereof and through which the pivot shaft extends. Below its radial pawl-operating arm 142 this three-armed lever has another or second radial arm 144 provided with a right angular rearwardly turned end 145 which normally engages beneath and in the path of forward movement of a stop lug 146 which projects from the forward face of the gear-forming operating member 75 near its toothed periphery and which is normally positioned at the right of and somewhat below its axis (Figs. 5, 6 and 7). Thus the stop lug 146 in engagement with the stop end 145 of the lever arm 144 normally positively locks the operating member 75 against forward rotation.

The third arm of this latch lever is an upstanding operating arm 147 which is bent or offset forwardly above the frame plate 12 so as to bring it just at the rear of the teeth of the star wheel 91 at the right hand thereof. The lever arm 147 is provided with a cam stud 148 having thereon a cam roller 149 which is normally seated between two of the teeth of the star wheel 91 and among its other functions serves to position the latter. The roller 149 is urged against the star wheel 91 by means of a coiled retractile return spring 150 for the three-armed lever as a whole, connected to the upper end of the upstanding arm 147 and anchored to the top of the main frame plate 12 (Fig. 3). It will be noted that the teeth of the star wheel 91, which are equidistantly spaced and shown as eight in number, have abrupt substantially radial driving faces to be engaged by the moving coin while the opposite faces of these teeth are inclined to form cams for rocking the lever arm 147 against the tension of its return spring 150.

Normally or when the coin carrier 76 carries no coin, upon forward or clockwise rotation of the handle knob 126 the coin carrier 76 will be rocked idly by its driving member or cam 118 while the driving disc 122 will rotate idly, its driving shoulder 136 freely passing beyond the disengaged clutch pawl 137, this idle movement of the coin-carrier, however, being utilized for discarding slugs of various kinds, some of which have been mentioned. When and as shown in Figs. 3 and 7 to 10 inclusive, the coin carrier 76 carries a coin 82, the initial movement of the coin carrier will first move this coin beyond the coin slot 83 in the lower front plate 10 and into contact with the adjacent lower tooth of the star wheel 91, the driving shoulder 136 of the driving disc 122 also being correspondingly moved to a slight extent towards the still disengaged coupling pawl 137, this being the phase of operation that is shown in Fig. 7.

The moving coin 82 now rotates the star

wheel 91 which rocks the three-armed latch lever in a clockwise direction, the movement of its upper arm 147 towards the right resulting in the inward movement of its lower arm 144 and in the raising of its intermediate arm 142. This upward movement of the lever arm 142 lifts its abutment-forming end above the pawl stud 141 and disengages the latter while at the same time the inward movement of the lower arm 144 moves its locking end 145 free from and out of the path of the stop lug 146 so that the operating member 75 is now set free to be rotated. As soon as the lever arm 142 has released the pawl pin 141 the pawl spring 139 becomes effective to rock the engaging end or shoulder of the pawl 137 into the path of the advancing driving shoulder 136 of the rotating driving disc 122, this shoulder now having moved forward closely adjacent to the pawl. The phase of operation just described is shown in Fig. 8, in which the clutch pawl or coupling pawl 137 has been set free and is at its engaging position just at the front of the driving shoulder 136 but with the rotatable operating member 75 still in its original or normal position, its rotation not having yet begun.

When the locking end or stop end 145 of the lower arm 144 has moved out of the path of forward rotative movement of the stop lug 146 on the operating member 75, this stop end 145 has moved into the path of rotation of a stop shoulder 151 formed on the forward face of the rotatable operating member 75. During any time that the locking end 145 is disengaged from the stop lug 146 the stop shoulder 151 will strike against this lever end 145 and will prevent any more than very limited rotation of the operating member 75 ahead of or independently of the rotation of its driving member 122. The purpose of this is to prevent the unlimited pulling out of the towel web 28 during this stage of the operation, and in the construction shown only a useless inch or so of the towel could be thus obtained. The normal space or lost motion shown as provided between its stop shoulder 151 and the locking end 145 provides for the movement of the latter into and out of the path of this lug 151 in a normal operation.

In the intermediate stage of the operation shown in Fig. 9, the operating member 75, coupled to its driving member 122, is being driven forward thereby while the coin carrier 76 is still moving forward and the lever arms 142, 144 and 147 on the three-armed latch lever have been rocked to the fullest extent by the rotating star wheel 91, in which the roller 149 is riding over the end of a tooth of the star wheel.

Fig. 10 shows a succeeding stage of the operation in which a star wheel tooth has passed beyond the roller 149 and the spring

150 has become effective to seat this roller between the teeth of the star wheel and to return the lever arms 142 and 144 to their normal position with the abutment-forming end of the former in the path of the pawl stud 141 and with the locking end 145 of the latter in the path of rotation of the stop lug 146.

The stop end 145 of the locking arm 144 has now moved out of the path of the stop shoulder 151 on the rotatable operating member 75 which, being clutched to its driving member 122, is rotating as a unit therewith and with the coin carrier cam 118. The coin carrier 76 has substantially reached the limit of its forward movement with its cam roller 117 just ready to escape from the end of the cam arm 118, which it will do at substantially the same time or immediately following the spring-returned movement of the star wheel roller 149, although this is substantially immaterial. When the cam roller 117 is released by the driving cam 118 the coin carrier 76 will be immediately returned to its normal position shown in Fig. 3 while the cam 118, the driving disc 122 and the gear-forming operating member 75 continue their rotation.

As the operating member 75 approaches the end of a single complete operating rotation, the pawl stud 141 will abut against the end of the returned pawl-controlling lever arm 142 and as the pawl 137 is carried forward by the driving shoulder 136 it will then rotate on its pivotal axis until it is rocked out of engagement with the driving shoulder 136, whereupon the driving member 122 may continue its rotation idly while the operating member 75 will be positively locked against further rotation by its stop lug 146 coming into engagement with the stop end 145 of the locking arm 144. It will now be understood that the above described coin-operated coupling device operates on the principle of and in fact constitutes one form of a one-revolution clutch.

It will be noted that at the end of a full rotation of the driving member 75, when its drive pawl 137 has been disengaged as above noted, the returned coin carrier 76, which has discharged its coin, will have been moved by its cam 118 away from its normal position and substantially to the position thereof shown in Fig. 8. Thus if the handle knob 126 should then be immediately released while the cam roller 117 is still in engagement with the cam arm 118, the coin carrier spring 99 in returning the coin carrier will be effective to rotate the driving disc 122 reversely to an extent which will properly space its driving shoulder 136 from the pawl 137 in their operating relation to the coin carrier. Hence it is immaterial in what rotative position the coin carrier cam 118 and the driving disc 122 may be left in their idle rotative movement. It is not deemed practicable to depend

upon the pawl pin 141 to stop the rotation of the operating member 75 and hence the stop lug 146 and locking lever end 145 are provided to form a strong and positive stop and lock for the operating member.

5 During the unitary rotation of the coin carrier cam 118, the driving disc 122 and the operating member 75 driven thereby, a second coin may be inserted through the slot 10 83 into the coin holding slot 81 of the returned coin carrier 76, in which case the abutment-forming end of the pawl-controlling lever arm 142 will be lifted out of the path of rotation of the pawl stud 141 in advance, as 15 the coin carrier moves the coin forward; thereby rotating the star wheel 91, as will be clear by an inspection of Figs. 7 and 8. Thus any number of coins may be successively inserted so that the operating member 75 may 20 be rotated continuously for thereby obtaining a strip of the paper towel web 28 of any length desired.

It is obvious that various modifications may be made in the construction shown in 25 the drawings and above particularly described, within the principle and scope of the invention as defined in the appended claims.

I claim:

1. In combination in a coin controlled 30 mechanism, a normally continuously idly rotatable driving member, a rotatable operating member which is normally idle and disconnected from said driving member, a normally 35 freely idly movable coin carrier, manually operable means independent of a coin for concomitantly operating the coin carrier and rotating said driving member in one direction to an unlimited extent, and a normally ineffective coupling device to be made effective by a 40 coin moved by the coin carrier to connect said operating member to said driving member to be driven thereby independently of the coin through the intermediary of the coupling device and then after said operating member 45 has been rotated to a predetermined extent said coupling device acting automatically to disconnect said operating member from said driving member.

2. In combination in a coin controlled 50 mechanism, a normally freely idly uninterruptedly rotatable driving member, a rotatable operating member which is normally idle and disconnected from said driving member, a normally 55 freely idly movable coin carrier which is normally in a coin-receiving position, manually operable means independent of a coin for continuously unidirectionally rotating said operating member to an unlimited extent and for concomitantly moving the 60 coin carrier repeatedly away from and causing its return to its coin-receiving position during such continuous rotation of the operating member, and a normally ineffective coupling device to be repeatedly made effective by coins successively supplied to the re- 65

turned coin carrier to connect and maintain such connection independently of the coin of the said operating member to said driving member to be continuously rotated thereby through the intermediary of the coupling device and said coupling device acting automatically to disconnect said operating member from its driving member after the operating member has been rotated thereby to a predetermined extent in the absence of a coin carried by the coin carrier. 70 75

3. In combination in a coin controlled mechanism, a coin carrier movable to and fro normally disposed at a coin-receiving position, means for moving the coin carrier away 80 from and causing it to return back to its normal position including a continuously rotatable driving member for the coin carrier, a second continuously rotatable driving member, a rotatable operating member which is 85 normally idle and disconnected from said second driving member, a positive connection between said driving members to compel their concomitant rotation, manually operable means including a handle for rotating said 90 driving members, and a normally ineffective coupling device to be made effective by a coin moved by the coin carrier to connect said operating member to said second driving member and thereafter automatically to disconnect it therefrom when said operating member has been rotated thereby to a predetermined extent. 95

4. In combination in a coin controlled mechanism, a rocking coin carrier normally 100 at a coin-receiving position, a return spring for the coin carrier, a continuously rotatable driving member for the coin carrier to rock it away from its normal position and release it to be returned by its spring while the driving 105 member continues its unidirectional rotation, a second driving member in axial alignment with the first and positively connected thereto for unitary rotation therewith, a rotatable operating member associated with the second 110 driving member in axial alignment therewith and relatively to which this second driving member is normally freely idly rotatable, manually operable means including a continuously 115 rotatable handle for continuously unidirectionally rotating both of said driving members for thereby repeatedly operating the coin carrier, and a normally ineffective coupling device to be repeatedly made effective by coins successively supplied to the returned coin carrier to connect and maintain such connection of the said operating member to said second driving member to be continuously rotated thereby and automatically to disconnect said operating member from its 120 said driving member after the operating member has been rotated thereby to a predetermined extent in the absence of a coin carried by the coin carrier. 125

5. In a coin controlled mechanism, the 130

- combination of a coin carrier normally disposed at a coin-receiving position and mounted to have to and fro movement regardless of whether or not it carries a coin, means including a continuously rotatable driving member for imparting to and fro movement to the coin carrier whether it carries a coin or not, means including a handle for rotating this driving member for thereby repeatedly operating the coin carrier to and fro, a movably mounted service-supplying member normally having no connection to the handle so as not to be operable thereby and to remain idle while the driving member 5 may be rotated by means of the handle to any extent for repeatedly operating the coin carrier when it carries no coin, and means dependent upon a coin carried by the coin carrier to establish an operating connection between the service-supplying member and the handle for transmitting service-supplying operating movement from the handle to the service-supplying member and whereby unlimited operation of the service-supplying 10 member may be effected by successively supplying coins to the returned coin carrier before it has been moved away from its coin-receiving position by the continued rotation of the rotatable driving member.
6. In a coin controlled mechanism, the combination of a coin carrier normally disposed at a coin-receiving position and mounted to be moved to and fro whether or not it carries a coin, a movably mounted handle, 15 means whereby a one-way movement of the handle imparts a complete to and fro movement to the coin carrier, a movably mounted service-supplying member normally having no connection to the handle so as not to be operable thereby and to remain idle while the coin carrier may be repeatedly operated without a coin being carried thereby, and means dependent upon a coin carried by the coin carrier to establish an operating connection 20 between the handle and the service-supplying member for transmitting operating movement to the latter and whereby unlimited operation of the service-supplying member may be effected by successively supplying coins to the returned coin carrier before it has been moved away from its coin-receiving position by initiating a repetition of the movement of the handle.
7. In a coin controlled mechanism, the combination of a coin carrier mounted for to and fro movement, a return spring for the coin carrier, a cam follower connected to the coin carrier, a continuously rotatable handle, a continuously rotatable cam connected to 25 the handle to cooperate with the cam follower and shaped to move the coin carrier against the tension of its spring and then to release the cam follower for the spring actuated return of the coin carrier while the cam may 30 continue its unidirectional rotation, a normally idle rotatable operating member, the rotation of which is to be utilized, normally disconnected from the foregoing elements so as not to be operable thereby, and means dependent upon a coin carried by the coin carrier to establish an operating connection by which rotation of the handle will transmit operating rotation to the said operating member, whereby coins may be successively supplied to the returned coin carrier for unlimited rotation of the operating member by the continued unidirectional rotation of the handle. 35
8. In a coin controlled mechanism, the combination of a coin carrier pivoted for rocking movement, a return spring connected to the coin carrier, a return stop for the coin carrier, a projection on the coin carrier, a handle having unlimited rotative movement, and a continuously rotatable cam arm connected to the handle to be rotated thereby to an unlimited extent on an axis parallel with the axis of the coin carrier and having a projecting end successively to move and release the coin carrier projection while the cam arm is rotating in one direction so that thereby the cam arm may continue its unidirectional rotation while the coin carrier will be returned by its spring. 40
9. The invention defined in claim 8, in combination with a normally idle rotatable operating member the rotation of which is to be utilized, and a coupling device for connecting the rotatable operating member to the cam arm for thereby imparting unidirectional rotation to the rotatable operating member, such coupling device including a normally ineffective clutch to be made effective by a moving coin carried by the coin carrier and to be automatically disengaged upon the completion of a predetermined extent of unidirectional rotative movement of the operating member unless another coin is supplied to the returned coin carrier and whereby the rotatable operating member may be rotated continuously by successively supplying coins to the coin carrier before the predetermined extent of rotative movement of the operating member has been completed. 45
10. In a coin controlled mechanism, the combination of a coin carrier mounted for to and fro movement, a return spring therefor, a continuously rotatable handle, operating connections between the handle and the coin carrier for successively moving the coin carrier against the tension of its spring and releasing it during the continued rotation of the handle, a normally idle rotatable operating member, the rotation of which is to be utilized, and a normally ineffective coupling device to be made effective by a coin moved by the coin carrier to impart limited rotation to the operating member during the rotation of the handle and including means which normally lock the rotatable operating member. 50

ber against operating rotation in its idle position and also including means to limit the operating rotation of the operating member independently of the rotation of the handle during an operating rotative movement of the operating member.

11. A coin controlled mechanism having, in combination, a normally ineffective freely 10 idle movable manually operable device including a handle and a coin carrier, a rotatable operating member, the rotation of which is to be utilized, normally idle and disconnected from said manually operable device, and normally ineffective connecting 15 means for causing movement of the manually operable device to transmit rotation to the operating member, said means including a normally disengaged one-way clutch to be engaged to connect the manually operable device to the rotatable operating member so that movement of the manually operable device will then transmit rotation to the operating member, a normally engaged disengagable stop for the rotatable operating member 20 in the normal idle position of the latter, a normally ineffective stop to be made effective to prevent free rotation of the operating member independently of said clutch during the time that said normally engaged stop 25 is disengaged, a part to be moved by a coin carried by the coin carrier, and means operated by said part for initially substantially concomitantly disengaging said normally engaged stop and engaging the disengaged 30 clutch and rendering said normally ineffective stop effective and for subsequently restoring said clutch and stops to their normal condition.

12. In a coin controlled mechanism, the 40 combination of a coin carrier mounted for to and fro movement, a return spring therefor, a continuously uninterruptedly rotatable driving member for the coin carrier to have driving engagement therewith during a part 45 only of its rotation in one direction and then to release the coin carrier so that the latter will be returned by its spring while the driving member continues its rotation in the said one direction, rotatable means including a 50 continuously uninterruptedly rotatable handle for manually rotating the driving member to an unlimited extent in the said one direction independently of a coin, a normally idle rotatable operating member, the rotation of which is to be utilized, which is normally disconnected from the driving member for the independent unlimited unidirectional rotation of the latter, and a coupling device 55 operable by a coin moved by the coin carrier first to connect the operating member to the driving member and subsequently acting automatically to disconnect it therefrom for the continued unlimited unidirectional rotation 60 of the driving member after the operat-

ing member has been rotated to a predetermined extent.

13. The invention defined in claim 12, in which the said coupling device comprises a normally disengaged clutch, a coin-driven part, and a clutch-operating member operated by said part. 70

14. In a coin controlled mechanism, the combination of a coin carrier mounted for to and for movement, a return spring therefor, a continuously rotatable driving member for operating the coin carrier, a second rotatable driving member coaxial with and connected to the first driving member for unitary rotation therewith and provided with an abrupt driving face, a normally idle rotatable operating member, the rotation of which is to be utilized, coaxial with the second driving member adjacent thereto and normally disconnected therefrom, a normally ineffective coupling pawl mounted on the operating member normally out of the path of the driving face on the second operating member and to be moved into such path thereby to be effective to couple the operating member to the second driving member for rotation therewith, a coin-driven member actuated by the coin moved by a coin carrier, and a pawl-controlling member operated by the coin-driven member first to render the coupling pawl effective and then to render it ineffective after the operating member has been rotated to a predetermined extent so that then the said driving members may continue their rotation independently of the rotatable operating member. 80

15. In a coin controlled mechanism, the combination of a coin carrier mounted for to and fro movement, a return spring therefor, a continuously rotatable driving member for operating the coin carrier, a second rotatable driving member coaxial with and positively connected to the first driving member for unitary rotation therewith and provided with an abrupt driving face, a normally idle rotatable operating member, the rotation of which is to be utilized, coaxial with the second driving member adjacent thereto and normally disconnected therefrom, a coupling pawl pivoted on the rotatable operating member and spring-pressed towards a position in which it will be engaged by the driving face of the second driving member, a member movable to and fro normally engaging with the coupling pawl to hold the latter at its disengaged position, and a cam device operated by a coin moved by the coin carrier to move the pawl-controlling member to and fro first out of engagement with the pawl and then back to its normal pawl-engaging position in which it will disengage the pawl from the second driving member when the operating member has made one complete rotation. 110

16. A coin controlled mechanism, comprising a coin carrier pivoted for rocking move- 120

ment, a return spring connected to the coin carrier, a return stop for the coin carrier, a cam follower carried by the coin carrier, a driving cam which is continuously rotatable on an axis parallel with the pivotal axis of the coin carrier and nearer thereto than said follower and having a radially projecting cam rise to engage the follower for rocking the coin carrier against the tension of its spring and then to release it while the cam continues to rotate, a rotatable drive member coaxial with the cam and positively connected thereto for unitary rotation therewith and provided with a peripheral driving shoulder, means including a handle for manually rotating the cam and the drive member, a normally idle rotatable operating member, the rotation of which is to be utilized, coaxial with the drive member adjacent thereto and normally disconnected therefrom, a normally disengaged pawl pivoted on the operating member and spring-pressed towards a position to be engaged by the driving shoulder on the drive member and provided with a projection to strike against an abutment as the operating member rotates thereby to disengage the pawl and hold it normally disengaged, a rocking pawl-controlling lever having an abutment-forming end movable out of and back again into the path of rotation of the pawl projection for permitting the pawl to become engaged and then to disengage the pawl and normally maintain it disengaged when the operating member has completed one rotation, and a cam-toothed coin-driven star wheel to be rotated a step by a coin moved by the coin carrier and engaging the pawl-controlling lever to cause the latter to be rocked away from and back to its abutment-forming position at each step of movement of the star wheel.

17. In a coin controlled mechanism, the combination of a coin carrier pivoted for rocking movement, a return spring connected to the coin carrier, a return stop for the coin carrier, a cam follower carried by the coin carrier, a driving cam which is continuously rotatable on an axis parallel with the pivotal axis of the coin carrier and nearer thereto than said follower to engage the follower for rocking the coin carrier against the tension of its spring and then to release it while the cam continues to rotate, means including a handle for manually rotating the cam, a normally idle rotatable operating member, the rotation of which is to be utilized, normally having no connection to the handle so as not to be operable thereby, and means dependent upon a coin carried by the coin carrier to establish an operating connection of the said operating member to the handle for transmitting limited operating rotation from the handle to the said operating member and whereby unlimited rotation of the operating member may be effected by successively sup-

plying coins to the returned coin carrier before the operating member has reached its limit of rotation.

In witness whereof, I hereunto subscribe my signature.
